UNITED STATES PATENT OFFICE.

HENRY E. LINDAS, OF COLORADO SPRINGS, COLORADO.

COLLAPSIBLE CONDUIT CORE.

Application filed April 7, 1926. Serial No. 100,267.

The present invention relates to conduit construction, and more particularly to molded conduit construction, where a collapsible core is used to form the central opening of a conduit.

An object of the present invention is to mold a conduit of cementitious material over a collapsible core, the core being constructed to facilitate its withdrawal after the material forming the conduit has set.

Another object is to mold a conduit over a collapsible core, comprising an inflatable inner portion and a collapsible outer portion.

In order to attain these objects, there is provided, in accordance with one feature of the invention, an elongated inflatable sleeve which may be of rubber or fabric, said sleeve being preferably expansible. Forming a sheath over this sleeve is a second sleeve which may be of fabric, said sleeve having the diameter when inflated of the interior of a conduit of which the combined sleeves form the central core.

These and other features of the invention, not specifically mentioned, will be more fully brought out in the following description and the accompanying drawing, wherein:

Figure 1, is a view in longitudinal section through a conduit made in accordance with the present invention, showing the collapsible core in the process of being withdrawn therefrom.

Figure 2, is a view similar to Figure 1, showing the core in position in a freshly molded portion of conduit.

Figure 3, is an enlarged longitudinal section of an inflated core, showing a method of mounting a wire therein and of clamping the ends of said core, a weighting chain being shown in position therein.

Figure 4, is a view in cross section of a molded portion of concrete, showing the collapsible core in position therein.

Figure 5, is a view in transverse section of a portion of conduit with a core support rack imbedded therein.

Figure 6, is a view in isometric perspective of an end plate; and

Figure 7, is a view in top and side elevation, respectively, of a transverse supporting element of the support rack shown in Figure 5.

Referring to the drawings in detail, a sleeve 1, which may be of canvas, is shaped to have the diameter of the inside opening of

a conduit of which the sleeve forms a portion of the core, the sleeve being somewhat longer than a section of conduit which it is desired to mold. An inner sleeve 2 is of inflatable material, such as rubber or tightly woven fabric. Where fabric is used for the inner sleeve and water is used as an inflating medium, a small quantity of water seeps through the outer sleeve and tends to float neat cement from the cementitious mixture of which the conduit is moulded into close proximity to the core. When the core is withdrawn this leaves a smooth, strong finish on the interior of the conduit. The structural features of the sleeves are unimportant, however, since the invention is intended to include any structure within the scope of the appended claims.

An inflating tube 3 may be clamped in one end of the inner sleeve to be in open communication with the interior thereof and to form a tight joint therewith, as by means of a clamp 4. The outer sleeve 1 may also be embraced by the clamp 4 to hold it in position. A wire 5 extends longitudinally of the interior of the sleeves 1 and 2, a gland 6, or other suitable means, being used to form an air-tight seal between the wire and the tube 3. A valve 7 provides means for connecting a pressure hose, not shown, to the tube by means of which air or water under pressure may be introduced into the interior of the core to inflate it. The ends of both sleeves 1 and 2 within the conduit are secured as by means of a second clamp 8, to close the end of the inner sleeve. A second inner sleeve 9 is connected to the clamp for a purpose to be brought out later in the specification. The ends of the inner sleeves 2 and 9 may be formed to closely encircle the tube 3 at one end and the wire 5 at the other to facilitate the making of a tight connection therewith. The ends of the outer sleeve 1 are, however, left the same size as the remainder of the sleeve so that the ends may be opened up to permit the withdrawal therethrough of the inner sleeve 2.

In using the core, a trench or trough 10 is formed of a size to mold the desired conduit therein. A metallic or wooden form of an ordinary type, not shown, may be placed interiorly of the ditch or trough to comprise a mold in which the material for the conduit is poured, but usually the trench itself may act as the mold. An end retaining plate 11 may

be placed across the end of a section of conduit which it is desired to mold, and a quantity of concrete, or other cementitious material, poured along the bottom of the trench. When a bed of sufficient thickness has been poured, a core, such as that shown in Figure 3, is placed in position on the bed of concrete, the end of the core projecting through the retaining plate 11, as shown in Figure 2. The inner end of the core is positioned within the portion of conduit previously poured, the division between the old and new sections being indicated by the line 20 in Figure 2. The core is then inflated by the introduction of air or water through the tube 3. Concrete, or other cementitious material, is then poured about the collapsible core to approximately the height shown in Figures 1, 2, and 4, and allowed to harden.

After the cementitious material has set, the valve 7 is opened, releasing the fluid from the interior of the core, whereupon the inner sleeve contracts due to its expansible nature sufficiently to free it from the outer sleeve 1. The clamp 4 is then removed, releasing the ends of the sleeves, and the gland 6 is released to free the wire 5. After releasing the fluid from the core, and opening up the end of the outer sleeve 1 to permit the withdrawal there-through of the inner sleeve 2, the wire 5, together with the inner sleeve 2, is drawn toward the open end of the conduit.

The clamp 8 on the inner end of the core is in engagement with the second inner sleeve 9, and as the wire 5 with the first inner sleeve 2 is drawn out of the conduit it draws the first inner sleeve 2 out of the outer casing 1 and simultaneously inverts the outer casing upon itself, causing it to ensheathe the second inner sleeve 9. This is caused by the slight adherence of the outer casing to the cementitious material of the conduit, said outer sleeve being slowly pulled away from the concrete as the end of the sleeve is drawn through the sleeve to invert it upon itself. The wire 5 is preferably long enough that when the conduit is completed and the collapsible core is withdrawn, the wire will still remain in the conduit to be used in drawing a cable therethrough.

When the first inner sleeve 2 is entirely removed from a molded section of conduit, the outer casing 1 will have been completely inverted upon itself and will ensheathe the second inner sleeve 9, the first inner sleeve 2 being entirely withdrawn from the outer sleeve. By removing the clamp 8 and placing it on the other end of the second inner sleeve and the outer casing which covers it, and connecting the inflating tube and a new inner core in the same relative positions as those shown in Figures 1 and 2 to this new assembly, the process may be repeated indefinitely.

In the making of long sections of conduit, and also where two or more passages are re-

quired in a conduit, it is sometimes necessary to weight the cores to make them of substantially the same specific gravity as the cementitious material of which they are molded to prevent them from floating from their proper position in the mold. This may be done by inserting a length of chain 12 in each of the inner sleeves or by using water, or other fluid, as an inflating medium. When the chain weighting means alone is employed, the chain 75 may be left permanently in the inner sleeves and is provided with a connection 14 at each end by which it may be attached to the central wire 5.

Anchor means are illustrated in Figures 80 5 and 7, having vertical rods 15 with offset portions at predetermined distances therein. The ends of the rods 15 may be forced into the bottom of the trench to be supported vertically thereby. Cross members 17, having hook-shaped end portions 18, are hooked into engagement with the offset portions 16 of the vertical rods 15 to retain the cores in position during pouring of the conduit. The rods 90 may extend above the conduit, as shown in Figure 5, so that if future requirements call for more passages in the conduit these may be constructed above the original conduit, using the projecting upper portions of the rods 15 to anchor the cores in position. 95

By properly weighting the cores and anchoring them at required intervals, long sections of conduit having several passages therethrough may be readily constructed in the manner specified. 100

I claim:

1. A collapsible conduit core, comprising inner and outer casings, the inner casing being inflatable and expansible, the outer casing being invertible and comparatively non-expansible.

2. A collapsible conduit core composed of a plurality of sleeves ensheathed one within the other, one of said sleeves being inflatable, and the other being invertible upon itself, 110 said core being removable from a cast conduit by withdrawing the inflatable sleeve and inverting the other of said sleeves to withdraw it.

3. A collapsible conduit core having a wire 115 therein, the core being composed of an inner sleeve and an outer sleeve; said core being removable from a cast conduit by telescopically withdrawing the inner sleeve from the outer sleeve and simultaneously inverting the 120 outer sleeve upon itself to withdraw it from the conduit.

4. A collapsible conduit core having a collapsible casing an inflatable sleeve therein the inner sleeve being removed by withdrawing it telescopically from a cast conduit while the collapsible casing is inverted inwardly upon itself to withdraw it. 125

5. A collapsible conduit core, comprising an inner inflatable sleeve, a wire connected there- 130

- through, and hermetically sealed thereto, and an outer comparatively inexpandable sleeve, an end of which may be opened to pass the inner sleeve therethrough.
- 5 6. A conduit core, comprising an outer sleeve, and an inner, inflatable sleeve, slidable within the outer sleeve, for the purpose set forth.
7. A collapsible conduit core, comprising inner and outer sleeves, the inner sleeve being 10 inflatable, and the outer sleeve being invertible independently of the inner sleeve.

In testimony whereof I affix my signature.

HENRY E. LINDAS.
